UNITED STATES PATENT OFFICE.

ARTHUR VERDESCA, OF WEST NEW YORK, NEW JERSEY.

AIR-HAMMER ATTACHMENT.

1,344,523.

Specification of Letters Patent. Patented June 22, 1920.

Application filed July 8, 1918. Serial No. 243,876.

To all whom it may concern:

Be it known that I, ARTHUR VERDESCA, a citizen of the United States, residing at West New York, in the county of Hudson, State 5 of New Jersey, have invented certain new and useful Improvements in Air-Hammer Attachments; and I do hereby declare the following to be a full, clear, and exact description of the invention, such as will enable others skilled in the art to which it appertains to make and use the same.

The invention relates to a "jack hammer" attachment and more particularly to the class of drill hole cleaning attachments for 15 compressed air hammers.

The primary object of the invention is the provision of an attachment of this character wherein the exhaust from the compressed air hammer may be directed into 20 the drill hole for the removal of the cuttings therefrom while the hammer is in operation, the attachment being of novel form and controlled by the operator of the hammer.

Another object of the invention is the provision of an attachment of this character wherein the air discharge nozzle thereof is readily detachable to permit the changing of drills in the hammer when the occasion requires, the connection of the nozzle being at a point opposite the chuck which holds the drill so that the removal of the nozzle leaves the operator free access to such chuck.

A further object of the invention is the provision of an attachment of this character which is extremely simple in construction, readily and easily applied to and removed from the compressed air hammer, 40 thoroughly reliable and efficient in its operation, and inexpensive to manufacture.

With these and other objects in view the invention consists in the features of construction, combination and arrangements of parts as will be hereinafter fully described, illustrated in the accompanying drawing and pointed out in the claim hereunto appended.

In the accompanying drawing:

Figure 1 is an elevation of a compressed air hammer showing the attachment constructed in accordance with the invention applied thereto.

Fig. 2 is a side elevation.

Fig. 3 is a fragmentary elevation of the upper portion of the attachment showing

the lower portion or the air discharge nozzle detached.

Fig. 4 is an elevation of the air discharge nozzle uncoupled from the upper portion of 60 the attachment.

Fig. 5 is a vertical longitudinal sectional view through the attachment.

Fig. 6 is a sectional view of the line 6—6 of Fig. 5.

Fig. 7 is a plan view of the coupling end 65 of the air discharge nozzle of the attachment.

Fig. 8 is a plan view of the coupling end 70 of the upper portion of the attachment.

Similar reference characters indicate corresponding parts throughout the several views in the drawings.

Referring to the drawings in detail, A designates generally the compressed air 75 motor, commonly known as the "jack hammer," having the usual air exhaust nipple B extending laterally at right-angles to the cylinder of the hammer, the latter being merely shown to illustrate the application 80 and the use of the attachment thereafter fully described.

The attachment comprises an elbow union 10 which is tapped or otherwise engaged in the exhaust nipple B and turned downward, 85 the T-shaped casing 11 of a three-way valve having a handle 13 and a lateral outlet 12 to the atmosphere, and a short pipe section 14 secured to the lower end of the valve casing and extending alongside the motor a 90 slight distance to one side thereof as best seen in Fig. 1. This pipe section carries at its lower end a male coupling head 15 for detachable engagement with a female or socket head 16 on the upper end of the air 95 discharge nozzle 17, which is formed with a bend 18 therein to provide an offset discharge end 19 which is adapted to extend parallel with, and in close relation to, the drill 20 of the compressed air hammer, the 100 nozzle 17 being of the proper length to bring its end 19 into close proximity to the cutting end of the drill. The latter is connected at its upper end by a chuck with the hammer within the motor, not necessary to 105 describe in detail, but attention is invited to the fact that said coupling heads stand about opposite this chuck so that, when the nozzle and its head are removed, the operator has free access to the drill for the insertion or the removal of the same.

Formed on the male coupling head 15 are

laterally extending guide ears 21, having suitable guideways for a pair of clamping jaws 22 adapted to slide through the ears 21, and arranged opposite each other, the jaws 22 being swingingly supported upon pivots 23, mounted in eyes 24 on a follower plate 25, slidably embracing the pipe section 14. This plate on moving in one direction, causes the opening of the jaws 22, and on 10 moving in the opposite direction causes the locking engagement of said jaws with a keeper plate 26 formed on the female head 16, and in this manner the air discharge nozzle is detachably locked to the pipe section 14 of the attachment.

Surrounding the pipe section 14 between the male coupling head 15 and the follower plate 25 is a coiled expansion spring 27 which serves to move the plate in a direction for closing the jaws in locking position. Formed on or secured to the male coupling head 15 is a post or upright 28 to which is pivotally connected a forked cam lever 29, the cam arms 30 of which pass astride the pipe 14 and bear upon the follower plate 25, and on swinging the lever 29 in one direction the plate is moved against the resistance of the spring 27 for the releasing of the jaws 22 from locked position with the follower plate, the lever 29 being normally raised and in contact with the upper pipe section 14 under the action of the spring 27 so that the jaws 22 will be in locking position.

35 The male coupling head 15 is formed with a reduced mouth 31 about which is a washer 32 and this mouth edge enters a socket within the female head 16 while the washer forms an air tight joint between the coupling heads when joined with each other.

In the use of the attachment the exhaust air from the hammer A is directed through

the pipe section 14 into the nozzle 17, whence it is discharged from the offset end 19 into the drill hole to clean and free said hole 45 from cuttings, dirt and other matter collected therein when the drill 20 is operated by the hammer A in the use thereof.

When it is desired to free the air from the attachment, the cock is set so that the air 50 will discharge from the outlet 12, and also by setting the cock the air can be regulated for the control of the attachment. It will appear that the nozzle 17 can be quickly detached when it is desired to remove the drill 55 20 or change one drill for another as the occasion may require.

From the foregoing it is thought that the construction and the manner of operation of the attachment in connection with the hammer will be clearly understood and therefore a more extensive explanation has been omitted.

What is claimed is:

The herein described attachment for a 65 drill driven by an air motor having a lateral exhaust, the same comprising an elbow adapted for connection with said exhaust, a three-way valve whose casing is carried by the elbow, a pipe section carried by said casing and extending alongside the motor, an air discharge nozzle adapted to be inserted in the tool hole alongside the drill and having its upper end deflected laterally, and detachable coupling means between said upper 70 end and the lower end of said pipe section at a point opposite the upper end of the drill.

In testimony whereof I affix my signature in the presence of two witnesses.

ARTHUR VERDESCA.

Witnesses:

M. MODARELLI,
DOMINICK MAINILRI.
